UNITED STATES PATENT OFFICE.

EDWARD W. DAVIS, OF MINNEAPOLIS, MINNESOTA.

APPARATUS FOR TREATMENT OF MAGNETIC ORE.

1,286,347.

Specification of Letters Patent.

Patented Dec. 3, 1918.

Application filed May 18, 1916, Serial No. 68,281. Renewed May 5, 1917. Serial No. 123,765.

To all whom it may concern:

Be it known that I, EDWARD W. DAVIS, a citizen of the United States, resident of Minneapolis, county of Hennepin, State of Minnesota, have invented certain new and useful improvements in Apparatus for Treatment of Magnetic Ore, of which the following is a specification.

In certain sections of the country considerable bodies of magnetite ore are found and to classify such ore it is desirable to demagnetize it, otherwise the small particles will adhere together in lumps or balls or to the larger particles and settle to the bottom of the classifier tank instead of floating to the top and becoming separated by the overflow.

The object, therefore, of my invention is to provide an apparatus by means of which the ore may be demagnetized and when once classified may be again magnetized and collected.

The invention consists generally in various constructions and combinations, all as hereinafter described and particularly pointed out in the claims.

In the accompanying drawings forming part of this specification,

The figure is a sectional view through a demagnetizing apparatus embodying my invention.

In the drawing, 2 represents a hopper having an open top 3 into which the ore is discharged through a spout 4. This hopper has an inclined spout 5 leading therefrom. A coil 6 encircles this spout 5 and through this coil an alternating current is passed, said coil being preferably cone shaped or tapered from the receiving end of the spout toward its discharge end. This has the effect of gradually reducing the influence of the alternating current on the magnetic ore and also prevents it from reaching a neutral point in the spout and remaining there, which it might do if the coil should be made of the same diameter from end to end. This alternating current, with its attracting and repelling force, eliminates the magnetic characteristics of the ore so that when it is delivered to the tank 7 beneath the discharge end of the spout section the finer particles will be completely demagnetized and free to float in the tank and, being comparatively light, will rise to the surface and overflow the edge of the tank into the receptacle 8, being carried thereby in the excess of water in the tank. A grav-

ity discharge opening 9 is provided in the bottom of the tank 7 having a valve 10 and a rod 11 by means of which the valve may be raised to permit the heavier lumps or pieces of ore to pass out of the tank, while the overflow carrying the light demagnetized particles will flow into the spout 12 which communicates at its lower end with a suitable box or receptacle 13. A coil 14 encircles the spout 12 and preferably corresponds in shape to the coil 6 having similar terminals, but instead of passing an alternating current through this coil I connect it with a direct current which has the effect of remagnetizing the particles of ore so that they will adhere to one another and drop into the box 13 in the shape of lumps or balls of ore particles. I am thus able, with this apparatus, to first demagnetize the small particles of ore to permit their convenient separation from the coarser non-floating pieces for the purpose of obtaining a rapid separation. Then, when the classification has been completed, I remagnetize these ore particles so that they will adhere together in lumps or balls and be more convenient for handling.

The device may be made in various sizes, according to the desired capacity.

I claim as my invention:

1. An apparatus of the class described comprising a gravity spout whereto the coarse and fine ore to be classified is delivered, a tank adapted to contain a supply of water for receiving the coarse and fine ore, and a coil, substantially cone-shaped in form, encircling said spout and having means for connection with an alternating current source.

2. An apparatus for the treatment of magnetite ore comprising a spout whereto the coarse and fine ore is delivered, a tapered coil encircling said spout and having means for connection with an alternating current source, a tank adapted to contain a supply of water whereto the demagnetized fine particles of ore are delivered to float in said tank and overflow the walls thereof, a second spout arranged to receive the overflow of said tank, a second tapered coil, said first and second coils being adapted for connection respectively with sources of alternating and direct currents of electricity.

3. An apparatus for demagnetizing ore comprising an alternating current coil cone-shaped, substantially, in form having means

for passing magnetite ore therethrough, and a classifier whereto the demagnetized ore is delivered.

4. An apparatus for demagnetizing ore comprising an alternating current coil having means for passing magnetite ore therethrough, a classifier whereto the demagnetized ore is delivered, and a direct current coil mounted to receive the demagnetized ore from said classifier.

5. An apparatus for demagnetizing ore comprising an alternating current coil having means for passing magnetic ore therethrough, and a fluid current gravity separator whereto the demagnetized ore is delivered.

6. An apparatus of the class described comprising a spout whereto the coarse and fine ore to be treated is delivered, a tank adapted to contain a supply of water for receiving the coarse and fine ore, and a coil encircling said spout and having means for connection with an alternating current source.

7. An apparatus for demagnetizing ore comprising an alternating current coil having means for passing magnetic ore therethrough, and a sizing apparatus whereto the demagnetized ore is delivered.

8. An apparatus of the class described comprising a fluid current gravity separator, an ore delivery spout therefor, and an electric coil encircling said spout, an ore dis-

charge spout for said separator, and an electric coil for said ore discharge spout, 35 said coils having conductors for alternating and direct currents respectively.

9. An apparatus of the class described comprising a gravity separator adapted to contain a supply of water, a gravity spout 40 for delivering ore to said tank, and an electric demagnetizing coil encircling said spout and having conductors communicating with a source of electrical energy.

10. An ore treating apparatus comprising a gravity separator, means for delivering magnetic ore thereto, and demagnetizing such ore during its delivery.

11. An apparatus for treating ore comprising a fluid current gravity separator having an overflow, means for demagnetizing the ore before delivery to said separator to effect a gravity separation therein, and means for re-magnetizing the lighter particles of ore discharged from said separator through 55 said overflow.

12. An apparatus for treating ore comprising an ore feeding means and means for demagnetizing particles of ore carried along by said feeding means, and means for separating the heavier from the lighter particles of ore when so demagnetized.

In witness whereof, I have hereunto set my hand this 15th day of May, 1916.

EDWARD W. DAVIS.
